[57] CLAIM

The ornamental design for a sliding door handle and lock assembly, as shown and described.

DESCRIPTION

FIG. 1 is a front perspective view of a sliding door handle and lock assembly showing our new design;

FIG. 2 is a rear perspective view thereof;

FIG. 3 is a front elevational view thereof, the opposite handle and lock assembly omitted for ease of illustration;

FIG. 4 is a rear elevational view thereof, the opposite handle and lock assembly omitted for ease of illustration;

FIG. 5 is a right side elevational view thereof;

FIG. 6 is a left side elevational view thereof;

FIG. 7 is a top plan view thereof; and,

FIG. 8 is a bottom plan view thereof.

The broken line showing of a portion of a door in FIGS. 1, 2 and 5-8 is for illustrative purposes only and forms no part of the claimed design.
